UNITED STATES PATENT OFFICE.

GURDON CONKLING, OF GLENS FALLS, ASSIGNOR TO THE CONKLING ORE DEPHOSPHORIZING COMPANY, OF NEW YORK, N. Y.

MAGNETIC SEPARATOR.

SPECIFICATION forming part of Letters Patent No. 406,337, dated July 2, 1889.

Application filed November 15, 1888. Serial No. 290,907. (No model.)

To all whom it may concern:

Be it known that I, GURDON CONKLING, a citizen of the United States, residing at Glens Falls, in the county of Warren and State of New York, have invented new and useful Improvements in Magnetic Separators, of which the following is a specification.

This invention relates to certain improvements in that class of magnetic separators which I have described in Letters Patent No. 383,863, granted to me June 5, 1888, said improvements being pointed out in the following specification and claims, and illustrated in the accompanying drawings, in which—

15 Figure 1 is a longitudinal vertical section in the plane $x x$, Fig. 3. Fig. 2 is a transverse vertical section in the plane $y y$, Fig. 3. Fig. 3 is a plan or top view, some portions being broken away in order to show the parts below. Fig. 4 is a perspective view of one of the covers.

Similar letters indicate corresponding parts.

In the drawings, the letter A designates a frame, which forms the bearings for the axles 25 of four rollers B B' B' B'. The rollers B B support the feed-belt D and the rollers B' B' the transverse belt C. E is a hopper placed over the feed-apron D.

30 In proximity to the transverse belt C, and inclosed by said belt or contained therein, are placed one or more magnets F, which may be made in the form of permanent magnets or in the form of iron plates, which are magnetized by the action of electro-magnets G, placed 35 upon them, as shown in the drawings. The magnets F are secured to traverses F', which are connected by screws $a a$ to the frame A, so that by means of said screws the magnets can be raised or lowered.

40 A hopper H is placed in suitable relative position to the transverse belt C, (see Fig. 2,) and a brush or scraper I acts on said transverse belt. Suitable receptacles J K are provided—one for the concentrated ore or iron 45 particles and the other for the gangue or refuse. A belt P, which extends round pulleys L M, is made to impart motion to the feed-belt D and also to the transverse belt C.

The feed-belt D is provided with raised rims

$b b$, which prevent the material to be treated 50 from passing off over the edges of said belt.

Over the feeding-section of the belt D, or over that portion of the same which is situated between the hopper E and the magnets F, is placed a cover N, which is held in position by screws $i i$ or other suitable fastenings, and which extends a certain distance beneath the edge of the transverse belt. When the pulverized ore, which is fed through the hopper E upon the feed-belt D, is carried by this 60 belt toward the transverse belt C, fine particles of iron are liable to be attracted by the magnets F and to be carried by the force of such attraction over the edge of the transverse belt. This disadvantage is guarded 65 against by the cover N. The discharging-section of the feed-belt D is covered by a cover O, which extends a certain distance over the edge of the transverse belt C, and which prevents iron particles contained in the 70 mass carried by the feed-belt from being carried over the edge of the transverse belt by the attraction of the magnets F.

The cover N is provided with flanges $n n$, (best seen in Fig. 4,) and if the feed-belt D is 75 provided with raised rims $b b$ said flanges $n n$ extend down on the inside of the rims $b b$ when the cover N is adjusted in its working position. (See Fig. 2.) By the combined action of the rims $b b$ and of the flanges $n n$ 80 the material carried by the feed-belt D is prevented from passing over the edges of said belt, and even the dust, which may become disengaged from said material by the rapid motion of the feed-belt and by the jar of the 85 machine, will be prevented from rising up and causing annoyance.

The magnets F extend in the direction of the length of the transverse belt C, and consequently in a transverse direction to the feed-belt D, Figs. 2 and 3, and their length is such that their ends extend beyond the edges of the feed-belt, Fig. 2. If the magnets F are placed transversely across the transverse belt C, the iron particles attracted by said magnets are liable to remain stationary while the belt C continues to move, and as the mass of the particles attracted by the magnets in-

creases the machine is liable to become clogged.

What I claim as new, and desire to secure by Letters Patent, is—

- 5 1. The combination, with the feed-belt, the transverse belt, and the magnet or magnets contained in said transverse belt, of a cover extending over the feeding-section of the feed-belt, substantially as described.
- 10 2. The combination, with the feed-belt, the transverse belt, and the magnet or magnets contained in said transverse belt, of a cover extending over the feeding-section of the feed-belt and beneath the edge of the transverse belt, substantially as described.
- 15 3. The combination, with the feed-belt, the transverse belt, and the magnet or magnets contained in said transverse belt, of two covers, one extending over the feeding-section and the other over the discharge-section of the feed-belt, substantially as described.
- 20 4. The combination, with the feed-belt, the transverse belt, and the magnet or magnets contained in said transverse belt, of two cov-
- 25 ers, one extending over the feeding-section

of the feed-belt and beneath the edge of the transverse belt and the other extending over the discharge-section of the feed-belt and over the edge of the transverse belt, substantially as described.

5. The combination, with the feed-belt, the transverse belt, and the magnet or magnets contained in sa'd transverse belt, of a cover provided on its under surface with flanges and extending over the feeding-section of the feed-belt, substantially as described.

6. The combination, with the feed-belt having raised rims at its edges, and with the transverse belt and the magnet or magnets contained in the transverse belt, of a cover provided with flanges n and extending over the feeding-section of the feed-apron, substantially as described.

In testimony whereof I have hereunto set my hand and seal in the presence of two sub-

scribing witnesses.

GURDON CONKLING. [L. S.]
